UNITED STATES PATENT OFFICE.

EMIL R. BUHTZ, OF SEATTLE, WASHINGTON.

SOAP-DISH ATTACHMENT FOR LAUNDRY TRAYS.

Application filed September 19, 1921. Serial No. 501,539.

To all whom it may concern:

Be it known that I, EMIL R. BUHTZ, a citizen of the United States of America, and resident of the city of Seattle, in the 5 county of King and State of Washington, have invented certain new and useful Improvements in Soap-Dish Attachments for Laundry Trays, of which the following is a specification.

10 My invention relates to laundry tubs and particularly to a dish designed for holding soap and like articles, which is especially adapted for attachment to laundry tubs and more particularly to laundry tubs which are 15 molded from cement or other analogous molded products.

The object of my invention is to provide a dish of this character which may be attached to laundry tubs at such a point and 20 in such a manner that it is out of the way, particularly for the application of a wringer and other articles to the tubs, and where it also makes conveniently accessible a bar of soap while providing a storage place there- 25 for which is thoroughly drained. Other objects of my invention will appear from a study of the following specification and the claims which terminate the same.

The features of my invention which I 30 believe to be new and upon which I desire to obtain a patent will be particularly set forth in the claims which terminate this specification.

In the accompanying drawings I have 35 shown my invention embodied in the form of construction which I now prefer to use.

Figure 1 is a top or plan view of a pair 40 of laundry tubs, showing my invention applied thereto, indicating the preferred location therefor.

Figure 2 is a transverse sectional elevation through the partition between the two tubs and the soap dish.

Figure 3 is a sectional elevation through 45 the soap dish and the partition, taken at right angles to that of Figure 2.

Figure 4 is a sectional elevation showing a modified type of construction for the soap dish.

50 In the use of laundry tubs it is very desirable to have provided a place where the soap may be placed when not in use and which will make it readily accessible when wanted. The location chosen by me for the soap dish, as best meeting these requirements, is at the top of the partition between

two tubs and next to the back wall of the tub. This leaves the larger part of the partition 10 between the two tubs 1, available for the attachment thereto of a wringer or any other piece of apparatus.

60 The soap dish 2, in the type of construction shown in Figures 2 and 3, is a shallow tray, preferably made of metal, having a drainage opening at the center of its length and width. This drainage opening 20 is made as a narrow slot extending transversely of the dish in the type of construction illustrated.

65 To the lower side of the dish and extending downwardly therefrom, is a drainage spout or conduit 3 which is preferably secured to the dish either by soldering or by casting it integrally therewith. Which of these constructions is adopted would depend largely upon the convenience and cheapness of manufacture. As shown in the drawings the drainage conduit 3 is supposed to be made as a separate piece and soldered to the bottom of the dish.

70 For better securing these together lugs 21 are provided at the bottom of the soap dish, which enter the upper flared end of the conduit 3 and thus secure the two in definite relation, as well as providing convenient surfaces for soldering the two together. For anchoring the soap dish in the 75 concrete of the partition wall 10, I have shown spurs, as 22, which project into the concrete.

75 The back side or edge of the soap dish is preferably provided with a flange, as 23, which slightly overlaps the back or rear wall of the tubs. Such rear wall is often provided with a finishing strip or band, as 11, of metal to which the flange 23 of the soap dish and also the back side of the soap dish may be soldered, or otherwise secured. The soap dish is thus securely held 80 in proper position.

85 It is common in the manufacture of cement laundry tubs to provide an overflow opening or conduit in the partition wall 10. Such an overflow conduit is shown at 4, being located near the back wall of the tubs 105 and in position so that the drainage conduit 3 from the soap dish may discharge thereinto. The inlet to the overflow conduit is shown as consisting of a short sleeve 5 provided with a discharge hole 50 in its lower side and a hole 51 in its upper side for the reception of the drainage from the 110

conduit 3. It has end plates as 52 which are provided with holes and are clamped at opposite sides of the partition 10 by means of a bolt 53.

- 5 In Figure 4 a modified type of construction is shown in which the bottom of the soap dish 2 is made slightly higher at the center than at the ends and drainage openings 25 are employed located towards the 10 ends of the dish so that the drip therefrom will fall into the tubs and not run down the central partition 10. To further insure dripping at a point where the soapy water will not stain the partition 10, a slightly de- 15 pending flange 26 may be provided at the inner side of the drainage openings 25. This will insure dripping of the water directly into the tub and prevent the possibility of its running back and down the partition. 20 What I claim as my invention is:
1. A soap holder for molded laundry trays comprising a metal dish having exteriorly projecting anchoring lugs positioned in a centrally disposed transverse band 25 and adapted to be anchored in a wall of the tub during the molding thereof.

2. A soap holder for laundry trays com-

prising a soap holding dish having exteriorly projecting anchoring lugs and a drainage opening contained within a transverse middle zone whereby it may be secured to a wall of a molded laundry tray during molding, and also having a marginal flange extending along an edge which is at right angles to said zone, said edge being 30 35 adapted to overlie a wall of the tub.

3. In combination a molded laundry tray having a central partition, a dish recessed into the upper edge of said partition, and anchored therein, the top of the dish being 40

45 as low as the upper edge of the tray.
4. In combination a molded laundry tray having a partition therein, an overflow connection through said partition, an overflow drainage conduit embedded in said partition, a metal soap dish recessed into the upper edge of said partition above said overflow connection, and a drainage channel connecting said dish and the overflow connection, and embedded in the partition.

Signed at Seattle, King County, Washington, this 13th day of September, 1921.

EMIL R. BUHTZ.
